A. B. Winger

United States Patent Office.

ASHBEL B. WINEGAR, OF SAN FRANCISCO, CALIFORNIA.

Letters Patent No. 79,425, dated June 30, 1868.

IMPROVEMENT IN MACHINE FOR KILN-DRYING.

The Schedule referred to in these Letters Patent and making part of the same.

TO ALL WHOM IT MAY CONCERN:

Be it known that I, ASHBEL B. WINEGAR, of the city and county of San Francisco, State of California, have invented a Machine for Kiln-Drying; and I do hereby declare the following description and accompanying drawings are sufficient to enable any person skilled in the art or science to which it most nearly appertains to make and use my said invention or improvement without further invention or experiment.

The object of my invention is to provide an improved kiln for drying salt and other substances that require to be kiln-dried before being reduced or prepared for market.

My invention consists in the construction of a furnace, of masonry or iron, circular in form, or any other shape, whose outline and dimensions shall answer the purpose.

Over the furnace is placed a drying-bed, or disk of iron or other material, the whole being surrounded by a rim with the necessary discharge-opening. A suitable vertical driving-shaft, having its step in the centre of the disk, is suspended by framework above the furnace, by means of which a series of radial arms, having hoes or stirrers, is rotated.

A feeding-hopper is also placed above the disk, and attached to the frame.

To more fully illustrate and describe my invention, reference is had to the accompanying drawings and letters marked thereon, of which—

Figure 1 is a side elevation.

Figure 2 is a plan.

A is the furnace, of suitable material to resist fire. Upon the top, I place a pan, B, to contain the article to be dried. The furnace is constructed with partition-walls, for the more even distribution of heat to the bottom of the disk or pan, shown in red. A door is placed at C, where the fuel is introduced, falling upon the grate-bars.

From the centre of this pan rises an upright shaft, F, having a step at F'. This shaft is moved by machinery, and carries radial arms G G G G. These arms have spindles H H H H passing through them, to the lower ends of which are attached hoes or stirrers I I I I. These spindles are made so as to form levers at the top, and have attached to them, by means of a crank, a movable bar, J, by which the stirrers are inclined inward or outward, as it becomes necessary to retain the material in the pan a longer or shorter period, or to discharge it when dry, which is done through the opening K in the rim of the pan, which is provided with a sliding door, K'.

A hopper, L, is placed above the pan, which discharges the salt into the pan, near its centre. This hopper is provided with a shaking-bottom or slide, O, connected by a short cord to a spring, P, placed at one side of the hopper. An extension-bar, R, is attached to the opposite end of the slide, to which a cord, S, is connected, which passes over grooved pulleys or rollers S' and S'', attached to the frame. Below the pulley S'' is placed a curved lever, T, which is attached to a cross-bar of the frame.

In applying the motive-power to the machine, by means of the pulley U, the teeth of the bevelled pinion U' strikes the end of the lever T, which causes the slide in the bottom of the hopper to vibrate to and fro, thereby insuring a more perfect and constant feeding to the pan, and when this auxiliary is not required in feeding, the cord is pulled taut, and confined to a pin, V, in a standard of the frame, and the lever is not actuated at all.

In operating the machine, the salt or other article to be dried is admitted to the pan through the hopper, which discharges near its centre, and the hoes are turned so as to spread the salt or other substance evenly over the surface of the pan. When this is accomplished, the hoes may be turned parallel to the radial arms, and kept in that position until the salt near the periphery is dry, when the hoes may be turned as desired, and the sliding door in the rim of the pan is raised, and the discharging commenced, into an elevator or other means, to be transported to the mill for grinding. Thus a continuous charging and discharging is had. The furnace may be so constructed that steam may be used for drying.

Having thus described my invention, what I claim, and desire to secure by Letters Patent, is—

1. A machine for drying salt and other substances, composed of the furnace A, pan or disk B, the radial arms G G, spindles H H, with the hoes or stirrers I I I attached to them, with the movable bar J, for turning them in different directions, so as to continually stir and turn the salt in the pan or discharge it at will from the periphery, the whole constructed and arranged to operate substantially as herein described.

2. The sliding board or plate O, at the bottom of the hopper, operated by the spring P, cords S, lever T, and bevelled pinion U, substantially as and for the purpose specified.

In witness whereof, I have hereunto set my hand and seal.

A. B. WINEGAR. [L. S.]
